CHILD'S BOOT

Edmund Bijak, Hawthorne, Calif.

Application September 19, 1955, Serial No. 37,979

Term of patent 3½ years

(Cl. D7—7)

FIG. 1.

FIG. 2.

FIG. 3.

FIG. 4.

FIG. 5.

Fig. 1 is a top plan view of a child's boot showing my new design;

Fig. 2 is a side elevational view;

Fig. 3 is a bottom plan view;

Fig. 4 is a front elevational view; and

Fig. 5 is a rear elevational view thereof.

I claim:

The ornamental design for a child's boot, substantially as shown.
